UNITED STATES PATENT OFFICE.

JOSEPH GROSS, OF PITTSBURGH, PENNSYLVANIA, ASSIGNOR OF ONE-HALF TO JOHN H. SMITH, OF PHILADELPHIA, PENNSYLVANIA.

CONCRETE FLOOR CONSTRUCTION.

Application filed May 18, 1927. Serial No. 192,304.

My invention refers to improvements in concrete floor construction, and relates particularly to reinforcing means for the ceiling portion, adapted for being permanently imbedded and made a part of the finished structure.

In modern practice of floor construction, the floor is formed of a continuous cast slab or body portion having regularly spaced 10 integral beam members, cast or poured around inverted U-shaped sheet metal forms, in connection with lower ceiling members of various construction.

My invention relates to an improved form 15 of ceiling member or lath, so constructed as to provide for ample stiffness and rigidity, open-work body portion for anchoring engagement by the concrete, transverse stiffening rib portions, and upwardly turned 20 terminal edge portions, for engagement with the downwardly disposed edge portions of the U-shaped member, together with other features of construction and improvement, as more fully hereinafter described.

Referring to the drawings, showing certain preferred embodiments of the invention,

Fig. 1 is a sectional view through a portion of a floor constructed according to my 30 invention;

Fig. 2 is a plan view of one of the ceiling reinforcing members, detached;

Fig. 3 is a partial perspective view of one end of said ceiling member;

Fig. 4 is a detail view showing the edge portion of such member bent inwardly between the reinforcing ribs, and over the flange of the floor form;

Fig. 5 is a partial plan view of the lath member showing a portion of the edge turned inwardly;

Fig. 6 is a plan view showing a modified construction;

Fig. 7 is a partial perspective view of a 45 modification of Fig. 3.

In concrete floor construction the main floor A is cast or poured as a continuous slab with spaced beam members a extending at intervals underneath the floor in the manner 50 of a beam.

The beams are formed between the downwardly extending leg portions 2 of the sheet metal forms 3, which are supported during

the pouring of the concrete, together with the ceiling lath members on false work or 55 other suitable framing. Forms 3 are provided at the lower edges of their end portions 2 with laterally extending flanges 4, projecting outwardly of the form.

Underneath the forms 3, where a ceiling is 60 desired, I provide the reinforcing ceiling members B. Said member consists generally of a horizontal section, preferably of sheet metal, having edge portions adapted to be bent upwardly around the flanges 4 where 65 desired for clamping engagement therewith.

Ceiling member B is generally trough-shaped, having a series of transverse upwardly extending rib members 6 of V-shape or other suitable form, and preferably im- 70 perforate for stiffness.

Between the several reinforcing ribs 6 the metal is open, either in the form of netting, perforated metal, expanded metal, or of any suitable open mesh construction, adapted to 75 permit of anchoring connection of the cement, plaster or other material forming the ceiling 5. Such expanded metal or open construction extends clear through from one edge to the other, and is upturned, as at 7, 80 together with upturned ends 8 of the several rib members 6, as in Fig. 3.

As thus constructed the member B is adapted to be laid up underneath and against the flanges 4 of the form 3, and to be bent 85 over thereon at intervals for clinching engagement therewith, as shown at 9, Figs. 1, 4 and 5. With such application, the ceiling member is firmly incorporated with the form 3, capable of providing a tight holding connection therewith, and of providing ample 90 and continuous anchoring connection for the ceiling layer 5.

In Fig. 6 I show a modified construction in which the main body portion of the ceiling lath member is composed of reticulated or perforate material of any suitable kind. The opposite edge portions are slotted inwardly, as at 10, providing for bending the upstanding sections 8 between alternately 95 arranged laterally extending sections 11. These may be bent over around the flanges 4 in the same manner as described, or if preferred the portions 11 may be bent over, leaving the parts 8 erect. With either construction the ceiling member will be firmly 100 105

anchored in the concrete when poured around these edge portions in forming the beam *a*, the upstanding parts 8 extending into and becoming firmly imbedded within the middle portion of the concrete beam.

In Fig. 7 I show a further modified construction in which the lath member is slotted at the edges at each side of the ribs 6, as at 12.

The ribs are turned upwardly as already described, leaving the open mesh intervening portions 13 extending beyond on a continuous plane. As thus made the lath may be located in position and some or all of the projecting portions 13 may be turned up around the flanges 4 of the forms 3, as desired. With either form of lath, it will be observed that the adjacent upstanding edges of the ceiling member extend inwardly from the sides of the beam and are closer together than the width of the finished beam.

Such arrangement allows the concrete to freely flow around each side of the upstanding edge portions of the ceiling member, completely imbedding and anchoring them within and between the sides of the beam.

The particular advantage of the construction is that it may be fabricated in the shop and delivered in the field with the upwardly turned edges at each side, ready for immediate application and connection to the forms 3, when these are placed, as in the ordinary practice.

The edge portions of either construction may be easily turned over in clamping connection with the flanges in the field, and when thus applied, and the concrete is poured over and between the forms, it will thoroughly and intimately anchor the ends of the lath members *B*.

When the reinforcing ceiling members are thus applied, the ceiling 5 may be applied in the usual manner, and will firmly adhere and become anchored to the open-mesh ceiling members *B* throughout their entire area.

The resulting floor structure contains all of the usual advantages of such reinforced lower ceiling construction, with a maximum strength and a minimum of material, with complete avoidance of any tendency to undue strain or fracture.

The ceiling lath of either of the forms shown are comparatively simple and inexpensive; they may be made in various sizes to suit the particular work in view; are easily and quickly applied by the workman; and can be compactly packed for shipment or storage.

The particular kind of open work or mesh between the reinforcing ribs is immaterial, and the forms 3 may also be made either of plane or corrugated metal. These and various other changes or modifications may be made by the skilled mechanic, and

all such are to be understood as within the scope of the following claims.

What I claim is:

1. A ceiling lath for concrete floor construction consisting of a flat reticulated metal portion having upwardly turned edge portions and intervening continuously straight portions co-extensive with the edge portions adapted to be bent over inwardly into holding engagement with an upper supporting outwardly flanged form member. 75

2. A ceiling lath for concrete floor construction consisting of sheet metal having a series of horizontally continuous transverse stiffening ribs with intervening open or expanded metal web portions and with its edges including the ribs bent up in the form of a trough, while maintaining the same shape of rib in the upstanding and entire horizontal portions, intervening edge portions between the bent up ribs being adapted for inward bending. 80

3. In concrete floor construction, the combination with an inverted U-shaped sheet metal form having laterally extending flanges, of a ceiling supporting member consisting of a sheet metal body having transverse supporting ribs extending from end to end on a common plane and having upturned ends and upwardly bent intervening edge portions adapted to be bent over between the upturned ends of the ribs and secured to said flanges, and providing for complete anchorage of the upturned rib terminals in the concrete body of the floor construction. 90

4. In combination with supporting form members for concrete floor construction having beam forming sides provided with flanges extending laterally beyond the sides, a transversely plane ceiling lath member of perforate material having upwardly extending edge portions adapted to extend upwardly beyond the flanges, and intervening edge perforate portions adapted to be bent over into holding engagement with the flanges. 100

5. In combination with supporting form members for concrete floor construction having beam forming sides provided with flanges extending laterally beyond the sides, a transversely plane ceiling lath member of perforate material having upwardly extending edge portions adapted to extend upwardly beyond the flanges, and intervening perforate edge portions adapted to be bent over inwardly into holding engagement with the flanges, at positions materially within the width of the concrete beam to be formed whereby to become anchored therein. 115

In testimony whereof I hereunto affix my signature.

JOSEPH GROSS.
